US00D364417S

United States Patent [19]

Winston

[11] Patent Number: Des. 364,417

[45] Date of Patent: **Nov. 21, 1995

[54] COMBINED RUBBER STAMP AND DISPLAY CARD

[76] Inventor: Jeffrey M. Winston, 658 W. Shore Dr., Anacortes, Wash. 98221

[**] Term: 14 Years

[21] Appl. No.: 23,937

[22] Filed: Jun. 3, 1994

[52] U.S. Cl. D18/15

[58] Field of Search 101/333-334,
101/327, 405-406, 371-373; D18/15, 17,
18; 118/264-270

[57]

CLAIM

The ornamental design for a combined rubber stamp and display card, as shown and described.

DESCRIPTION

FIG. 1 is a perspective view of a combined rubber stamp and display card showing my new design;

FIG. 2 is a front elevational view thereof;

FIG. 3 is an elevational view of a first side thereof, the other side view being identical;

FIG. 4 is a rear elevational view thereof;

FIG. 5 is a top plan view thereof; and,

FIG. 6 is a bottom view thereof.

The broken lines are for purposes of illustration only and form no part of the claimed design.
